[57] CLAIM

The ornamental design for a powder spray gun, as shown and described.

DESCRIPTION

FIG. 1 is a front and side perspective view of the powder spray gun of this invention;

FIG. 2 is a side elevational view of the powder spray gun of FIG. 1 taken from the right hand side thereof;

FIG. 3 is a side elevational view of the powder spray gun of FIG. 1 taken from the left hand side thereof;

FIG. 4 is a top plan view of the powder spray gun of FIG. 1;

FIG. 5 is a bottom plan view of the powder spray gun of FIG. 1;

FIG. 6 is a rear elevational view of the powder spray gun of FIG. 1;

FIG. 7 is a front elevational view powder spray gun of FIG. 1;

FIG. 8 is a front and side perspective view of another embodiment of this invention shown similar to FIG. 1;

FIG. 9 is a side elevational view of the powder spray gun of FIG. 8 taken from the right hand side thereof looking along the length from the tip shown at the left hand side of FIG. 8;

FIG. 10 is a side elevational view of the powder spray gun taken from the side opposite FIG. 9;

FIG. 11 is a top plan view of the powder spray gun of FIG. 8;

FIG. 12 is a bottom plan view of the powder spray gun of FIG. 8;

FIG. 13 is a rear elevational view of the powder spray gun of FIG. 8; and,

FIG. 14 is a front elevational view of the powder spray gun of FIG. 8.
